(57) **CLAIM**

The ornamental design for a LED icicle lights assembly, as shown and described.

DESCRIPTION

FIG. 1 is a front, right, and top perspective view of LED icicle lights assembly, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising a plug; and,

FIG. 9 is an exploded view of the plug of the LED icicle lights assembly.

The broken lines shown in the drawings are included for the purpose of illustrating portions of the LED icicle lights assembly that form no part of the claimed design.

The cables are shown with a symbolic break in its length. The appearance of any portion of the article between the breaks lines forms no part of the claimed design.
